UNITED STATES PATENT OFFICE.

HARRISON H. EATON, OF BEVERLY, MASSACHUSETTS, ASSIGNOR TO UNITED SHOE MACHINERY COMPANY, OF PATERSON, NEW JERSEY, A CORPORATION OF NEW JERSEY.

LINING-PROTECTOR.

1,119,750.

Specification of Letters Patent.

Patented Dec. 1, 1914.

Application filed May 28, 1913. Serial No. 770,356.

To all whom it may concern:

Be it known that I, HARRISON H. EATON, a citizen of the United States, residing at Beverly, in the county of Essex and State 5 of Massachusetts, have invented certain new and useful Improvements in Lining-Protectors; and I do hereby declare the following to be a full, clear, and exact description of the invention, such as will enable others 10 skilled in the art to which it appertains to make and use the same.

The present invention relates to heel supports for shoe lasts and more particularly to devices employed in connection with such 15 supports to prevent injury to the lining and upper of a lasted shoe.

When jacking a shoe the heel portion of the last is forced down upon the last pin until the last contacts with the face of the 20 last block and unless considerable care is exercised in performing this operation the upper and lining of the shoe are often caught between the adjacent faces of the last and last block and when pressure is applied to 25 the shoe the upper is cut or otherwise damaged.

The object of the present invention is to provide a simple, compact and efficient mechanism which engages and positively 30 spreads the upper of a shoe as the last is forced down upon the last pin.

With this object in view, one feature of the invention consists in the provision of an upper spreading member located substantially 35 parallel to the upper and arranged to move outwardly to spread the upper as the shoe last is forced down on to the last pin.

Still further features of the invention consist in certain novel features of construction, 40 combinations and arrangements of parts hereinafter described and claimed, the advantages of which will be obvious to those skilled in the art from the following description.

45 In the accompanying drawings illustrating the preferred form of the invention; Figure 1 represents a side elevation of a heel support embodying the invention; Fig. 2 is an end elevation of the construction shown in Fig. 1 and illustrates the upper spreading devices in the position which they normally occupy before the last is mounted upon the heel support; and Fig. 3 is a view similar to Fig. 2 illustrating the position of

the upper spreading members after the last 55 has been forced down upon the last pin into engagement with the last block.

The illustrated embodiment of the invention is preferably employed in connection with a sole laying machine of the type disclosed in the U. S. application of Davenport, No. 586,243, filed October 10, 1910, but it is understood that the improvement is not limited in its application to this type of machine, but may be used to advantage in 60 various machines in which the last is supported other than manually.

The heel support which is indicated at 1 is mounted in the machine in the usual manner and consists of a last block 2 and a last 70 pin 3 extending therefrom. The upper spreading device is supported substantially parallel to the upper in a position to be engaged by the last in its movement toward the last block and move outwardly upon a 75 continued movement of the last to engage the inside of the depending upper and move it away from the last pin. In the simplest the most efficient form of the invention which has yet been devised the upper 80 spreading member is supported upon the free end of an arm pivoted to the last block at one side of the last pin and extending obliquely to the opposite side of the last pin. In the illustrated embodiment of the 85 invention two upper spreading members 4 are supported upon opposite sides of the last pin and are arranged to move in opposite directions away from the last pin upon a downward movement of the last. The opposite ends of the members are supported 90 by arms 5 and 6 which are pivoted respectively in transverse slots 7 and 8 formed in the upper face of the last block. As shown clearly in Fig. 2, each arm is pivoted 95 at one side of the last pin and extends obliquely of the last pin to a point at the opposite side, thus causing the upper spreading member to move downwardly and outwardly when it is engaged by the last into 100 the position shown in Fig. 3. In order to retain the members in close proximity to the last pin when the last is removed, the lower ends of the arms 5 are provided with depending ears 10 which are connected by a 105 tension spring 11. This construction forms a simple and efficient mechanism which occupies but little space and which operates

with certainty to spread the upper away from the last pin when the shoe is mounted upon the heel support.

While it is preferred to employ the specific construction and arrangement of parts shown and described, it will be understood that this construction and arrangement is not essential except so far as specified in the claims, and may be changed or modified 10 without departing from the broader features of the invention.

The invention having been described, what is claimed is:—

- 15 1. A heel support for a last, having in combination, a last block, a last pin mounted upon the block, and an upper spreading member normally supported in close proximity to the last pin and arranged to move outwardly away from the last pin to positively spread the upper as the shoe last is forced down on to the last pin.
- 20 2. A heel support for a last, having in combination, a last block, a last pin mounted upon the block, and an upper spreading member normally supported in close proximity to the last pin and constructed and arranged to move outwardly away from the last pin and toward the upper face of the last block to positively spread the upper as 30 the last is forced down on to the last pin.
- 25 3. A heel support for a last, having in

combination, a last block, a last pin mounted upon the block, an arm pivoted to the last block at one side of the last pin and extending obliquely to the opposite side of 35 the last pin, and an upper spreading member supported upon the free end of the arm and arranged to be engaged by the last as the latter is forced down on to the last pin.

4. A heel support for a last, having in 40 combination, a last block, a last pin mounted upon the block, an arm pivoted upon the last block at one side of the last pin and extending to the opposite side of the last pin, an upper spreading member supported 45 upon the free end of the arm, and a spring normally maintaining the upper spreading member in engagement with the last pin.

5. A heel support for a last, having in 50 combination, a last block, a last pin mounted upon the block, a pair of arms pivoted upon the last block at opposite sides of the last pin, an upper spreading member supported upon the free end of each arm, and a spring connecting the lower ends of the 55 arms to retain the upper spreading members in engagement with opposite sides of the last pin.
